UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FILLING-CARRIER SUPPORT FOR AUTOMATIC FILLING-REPLENISHING LOOMS.

Application filed October 19, 1922. Serial No. 595,546.

To all whom it may concern:

Be it known that I, ALONZO E. RHOADES, a citizen of the United States, and resident of Hopdale, county of Worcester, State of Massachusetts, have invented an Improvement in Filling-Carrier Supports for Automatic Filling-Replenishing Looms, of which the following description, in connection with the accompanying drawing, is a specification, like characters on the drawing representing like parts.

This invention relates to improvements in filling carrier supports for automatic filling replenishing looms and the object thereof is to provide an improved and simplified construction for mounting the filling carrier support in such a manner that it may have both a pivotal and a lateral swinging movement.

More particularly the invention relates to means for so mounting the filling carrier support of the character above described that a single resilient means will serve to maintain the filling carrier support in normal position to hold a positioned filling carrier in the hopper and which will permit a combined pivotal or tilting and lateral bodily movement of the filling carrier support when the filling carrier is forced from the hopper into the shuttle.

A further object of the invention is to provide a mounting for a filling carrier support comprising a swinging arm carried by the hopper stand which will have an extended bearing for the filling carrier support and thereby provide a more rigid construction which is less likely to be broken by the vigorous stroke of the filling carrier thereupon during transfer and which will yield sufficiently in case the filling carrier is improperly positioned to avoid a smash.

The present invention may be stated to embody certain improvements upon the construction illustrated in Patent No. 1,350,093, granted August 17, 1921 to Harry A. Davis, and also to embody certain features of construction disclosed in my Patent Number 1,452,655 granted April 24, 1923, for improvements in filling carrier supports for looms.

A preferred embodiment of the invention is illustrated herein as applied to the well known "Northrop" type of loom.

In the drawings:

Fig. 1 is an end elevation, partly in ver-

tical cross section, of so much of an automatic filling replenishing loom as is necessary to the disclosure of the invention; and,

Fig. 2 is a plan view, partly in transverse cross section, of the filling carrier support 60 and the arm upon which it is pivotally mounted.

The loom, a portion of which is illustrated to disclose a preferred form of the invention, is that of the well known "Northrop" 65 type and as this type of loom is familiar to those skilled in the art, and as the present invention relates only to the filling carrier supporting mechanism, no extended description of the loom or its operation is necessary. 70

Such a loom comprises the usual side frame 1, breast beam 2, lay 3, a magazine or hopper for containing a supply of fresh filling carriers (not shown) and a transferrer 4 for transferring a fresh filling carrier 5 75 from the hopper to the shuttle 6 of the lay when the running filling has become substantially or wholly exhausted.

The magazine or hopper comprises a stand 7 which is usually secured to the breast beam at one end of the loom and a hopper plate 8 which rises vertically from the hopper stand and upon which the hopper is rotatably mounted.

The foremost filling carrier 5 in the hopper is brought into transferring position by intermittent rotation of the hopper in the usual manner and when in such position is usually brought up against and arrested by a guide or abutment 9 by which it is guided 85 into the shuttle when it is forced from the hopper by the action of the transferrer.

The filling carrier 5, when in this position, is usually supported on the side opposite the abutment 9 by a tilting filling carrier support which yields when transfer takes place to permit the filling carrier to pass downwardly into the shuttle. When transfer is called for a dog 10, carried by the trans- 95 ferrer, is positioned in the path of a bunter 100 11 upon the lay so that during the forward movement of the lay the transferrer is actuated to strike a sudden sharp blow upon the filling carrier which drives it with considerable force into the shuttle and the filling carrier support is, therefore, swung 105 downwardly by the same sudden force. In case the filling carrier is improperly positioned a smash is likely to take place. In the present construction the filling carrier

110

support is pivotally mounted upon the lower end of a swinging arm which is pivoted at its upper end upon the hopper plate 8 so that the filling carrier support not only yields pivotally in the normal action of the trans-
ferrer, but also yields laterally in case an improperly positioned filling carrier is struck by the trans-
ferrer arm so that a smash will be avoided.

10 In a similar previous construction, disclosed in the patent to Davis above referred to, separate resilient means are provided for controlling the tilting movement of the filling carrier support and the swinging movement of the arm upon which it is pivotally mounted.

15 In the present invention the filling carrier support is so mounted that a single resilient device serves to position a filling carrier and to permit both the tilting movement and the bodily swinging movement thereof.

20 The invention further contemplates the provision of a novel mounting for the filling carrier support upon the swinging arm which is similar in some respects to the construction disclosed in my prior application above referred to.

25 In the preferred form of the invention illustrated herein the hopper plate 8 is provided with a laterally extending boss 12 upon which is pivotally mounted a swinging arm 13 which is provided at its lower end with an internally threaded boss 14 the
30 threads of which terminate short of one end of the boss.

35 As illustrated herein the boss 14 is threaded in from the right hand end leaving the exit portion 15 unthreaded and consequently
40 of the original diameter of the bore into which the threaded portion is cut.

45 The lower end of the arm 13 is provided with a long shaft or journal for the filling carrier which is provided with a bearing section 16, an intermediate threaded section 17 and a bearing section 18 of smaller diameter than the section 17 adapted to pass through the unthreaded portion 15 of the boss 14.

50 When the shaft is screwed into place it will be locked by the jamming of the threaded portion as it reaches the unthreaded end portion of the boss.

55 The bearing section 16 also may be made of greater diameter than the internal diameter of the threaded boss 14 so that the shaft will also be locked when screwed into place by the unthreaded bearing section 16 engaging the end of the boss. It will be
60 understood, however, that either or both of these means of locking the shaft in position may be employed as may be desired.

65 The filling carrier support as illustrated herein is preferably in the form of a U-shaped plate or frame 19, one arm 20 of

which constitutes the filling carrier support proper and normally extends in a generally horizontal position beneath the positioned filling carrier 5. The other arm 21 of the filling carrier support extends upwardly and is provided with a bifurcated end 22 which receives a stud or bolt 23 and engages a nut 24 forming a head thereof. The bolt 23 is slidably mounted in an aperture, somewhat larger than the bolt, in a lug 25 which projects from the hopper plate 8 and a helical compression spring 26, surrounding said bolt, is located between said lug and a head 27 upon the upper or other end of the bolt 23.

70 The arms 20 and 21 of the yoke-shaped frame are provided with alined bearings adapted to fit accurately upon the respective bearing sections 16 and 18 of the journal shaft. These bearings, in the preferred 75 form of the invention, extend into and through elongated bearing bosses 28 and 29 which project externally from the arms of the yoke-shaped frame as illustrated. The filling carrier support, thus provided with 80 long extended bearings, is very strong and rigid and is able to withstand the sudden and heavy blows applied by the trans-
ferrer even under unusual conditions such as are 85 due to an improperly positioned filling carrier. Furthermore, the rigidly locked connection of the journal shaft to the boss 14 of the swinging arm 13 and the long ex-
tended bearings of the filling carrier sup-
port provides a rigid construction which 90 will not be bent or broken by the vigorous 95 strokes of the trans-
ferrer either under normal conditions or where a filling carrier is 100 improperly positioned when struck by the 105 trans-
ferrer.

110 In the operation of the device, upon call for transfer, the dog 10 of the trans-
ferrer is positioned in the path of the bunter 11 on the lay so that as the lay beats up the trans-
ferrer is swung about its pivot and its head strikes vigorously upon the positioned filling carrier driving it from the hopper into the shuttle. As the filling car-
rier is thus driven downwardly it is di-
rected by the guide 9 and the arm 20 of 115 the filling carrier support into the shuttle. During this movement the filling carrier supporting arm 20 tilts or rocks about the pivotal shaft upon which it is mounted, the spring 26 being compressed by such 120 pivotal movement. As the arm 21 swings away from the lug 25 upon the hopper stand during such movement the spring 26 permits the depending arm 13, upon which the filling carrier support is mounted, to 125 swing about its pivot 12 so that the filling carrier support has both a tilting and a bodily swinging movement. By reason of this construction, therefore, the movement of the filling carrier support is partially a 130

pivotal or tilting movement and partially a bodily swinging movement which acts more effectively to guide the filling carrier into the shuttle than the pure tilting movement of the filling carrier supports of the old type. Furthermore, if by chance a filling carrier is misplaced the combined tilting and yielding bodily movement of the filling carrier support will permit the filling carrier to be forced sufficiently out of the path of the transerrer head to enable the latter to complete its full movement without danger of breakage of the hopper plate 8 or of the hopper stand itself.

15 It will be understood that the embodiment of the invention disclosed herein is illustrative and not restrictive and that various changes in form, construction and arrangement of parts may be made within the 20 spirit and scope of the following claims.

Having thus described my invention, what I claim as new, and desire to secure by Letters Patent, is:

1. In an automatic filling replenishing loom comprising a hopper plate having a laterally extending lug, transferring mechanism, and means for arresting the filling carriers in said hopper successively in transferring position, a swinging arm, a filling carrier support pivotally mounted on said swinging arm having an upwardly extending member and a resilient device acting upon the upwardly extending member normally to hold it in contact with said lug and thereby position the support beneath the filling carrier which is positioned for transfer and adapted to permit both pivotal movement of said filling carrier support and swinging movement of said arm when the filling carrier support is engaged by the filling carrier being transferred.

2. In an automatic filling replenishing loom comprising a hopper plate having a laterally extending lug, a hopper, transferring mechanism, and means for arresting the filling carriers in said hopper successively in transferring position, a swinging

arm pivotally mounted on said hopper plate, a filling carrier support pivotally mounted on said swinging arm having means for supporting the positioned filling carrier in the hopper and an upwardly extending arm and means including a resilient member connecting said upwardly extending arm with the lug upon said hopper plate acting to position the filling carrier support normally beneath the filling carrier which is positioned for transfer and adapted to permit both pivotal movement of said filling carrier support and swinging movement of said arm when said filling carrier support is engaged by the filling carrier being transferred.

3. In an automatic filling replenishing loom comprising a hopper plate, a hopper, transferring mechanism and means for arresting the filling carriers in said hopper successively in transferring position, a swinging arm pivotally mounted at its upper end on said hopper plate and provided at its lower end with an internally threaded boss, a shaft having end bearing sections and an intermediate threaded section fitting said boss, the diameter of one bearing section being less, and the diameter of the other bearing section being greater, than the internal diameter of the threaded boss, whereby when the shaft is screwed into the boss it is locked in place, a yoke-shaped filling carrier support having its arms journaled on the respective bearing sections of said shaft, and resilient means connecting one of the arms of said filling carrier support with said hopper plate acting normally to retain the filling carrier support beneath the positioned filling carrier and adapted to permit pivotal movement of said filling carrier support and lateral movement of said swinging arm when the filling carrier support is engaged by the filling carrier being transferred.

In testimony whereof, I have signed my name to this specification.

ALONZO E. RHOADES.
